United States Patent Office

Des. 229,983

Patented Jan. 15, 1974

229,983

PIPE REAMER AND TAMPER

James E. Bernard, Stilwell, Kans., assignor to Richard W. Whitlaw, Milbank, S. Dak.

Filed Feb. 7, 1972, Ser. No. 224,405

Term of patent 14 years

Int. Cl. D27—99

U.S. Cl. D85—7 D

Fig. 1.

Fig. 2.

FIG. 1 is a side elevational view of a pipe reamer and tamper showing my new design; the left end being flat and unornamented; and

FIG. 2 is a right end elevational view thereof.

I claim:

The ornamental design for the pipe reamer and tamper, as shown and described.
